UNITED STATES PATENT OFFICE.

ROBERT S. CADE, OF CANTON, OHIO.

CONCRETE PAVING-SLAB.

1,371,856.

Specification of Letters Patent. Patented Mar. 15, 1921.

Application filed April 15, 1919. Serial No. 290,178.

To all whom it may concern:

Be it known that I, ROBERT S. CADE, a citizen of the United States, residing at Canton, in the county of Stark and State 5 of Ohio, have invented new and useful Improvements in Concrete Paving-Slabs, of which the following is a specification.

This invention relates to building materials and has for its object the provision 10 of a concrete slab adapted for use in paving roadways, cellars, porch floors, and the like, the slab having its ends so formed that when a plurality of slabs are arranged in end to end relation the meeting ends will be inter- 15 engaged and positively locked against relative upward or downward displacement of any end whereby a very strong joint will be provided which is incapable of dislocation.

20 An important object is the provision of a slab of this character, the ends of which are so constructed that when the ends of adjacent slabs are interengaged the joints therebetween will permit of the necessary 25 expansion and contraction of the slabs under the influence of heat or cold so that danger of cracking the slabs will be avoided.

Another object is the provision of a slab 30 of this character which will be very simple and inexpensive in manufacture, highly efficient in use, durable in service, and a general improvement in the art.

With the above and other objects and advantages in view, the invention consists in 35 the details of construction to be hereinafter more fully described and claimed, and illustrated in the accompanying drawing, in which—

The figure is a longitudinal sectional view 40 through a plurality of blocks or slabs constructed in accordance with my invention and arranged in interengagement.

Referring more particularly to the drawing, the numeral 10 designates the body of 45 the slab which may be of any desired dimensions and which is formed of any preferred mixture of concrete or the like and which may or may not be provided with longitudinal reinforcing members 11 which 50 may be fluted iron, brass, wire netting, or in fact any of the standard devices used for this purpose.

At one end the slab is formed with a downward and outward extension 12 and 55 this end will, for the sake of clearness, be hereinafter designated as the female mem-

ber of the joint between two successive slabs. This extension 12 is provided in its upper face with a recess 13 which extends beneath the shoulder 14 formed at the end 60 of the slab so that that shoulder is also an overhang, as shown at 15. At its other end the slab is provided with an extension 16 of a size and shape to fit comparatively snugly 65 within the recess 13 and under the overhang 15, with the end of the slab proper engaging against the shoulder 14 of the next adjacent slab. The end of the slab provided with the extension 16 will be hereinafter referred to as the male member of the joint between the 70 slabs.

In assembling a plurality of slabs in building a roadway or floor, the extension 16 constituting the male member is engaged within the recess 13 of the next adjacent 75 slab with its extremity engaging beneath the overhang 15, as will be obvious from an inspection of the drawing. This engagement may be effected by tilting the adjacent ends of two slabs relatively or it may be 80 effected by sliding one slab laterally with respect to the next adjacent slab. When the slabs are connected by the above described joint, it will be seen that relative upward displacement of either of the meeting ends 85 of successive slabs will be prevented by engagement of the extension 16 beneath the overhang 15. The usual metallic edge plates 17 may be provided at the upper edges of the ends of the slabs for making the proper 90 joint.

From the foregoing description and a study of the drawing it will be apparent that I have thus provided an extremely simple and inexpensive paving slab which is 95 so constructed that a plurality of slabs may be interengaged in end to end relation with simplicity and ease and with the result that a joint will be provided which will be very secure and strong inasmuch as displacement 100 of the meeting ends upwardly or downwardly with respect to each other will be prevented.

Having thus described my invention, I 105 claim:

A concrete slab comprising an elongated body having its ends formed as square shoulders, a downward and outward extension formed at one end of said body and having its upper surface lying in the same 110 plane as the lower surface of the body of the slab, the upper surface of said exten-

sion being recessed and said recess extending beneath the adjacent shoulder whereby to provide an overhang, and an extension formed on the other end of the slab and extending from and beyond the lower side thereof, said last named extension being of a size and shape whereby to conformingly

engage within the recess in the first named extension on the next adjacent slab, and a tongue extending from said second named extension and engaging beneath the overhang at the end of the next adjacent slab.

In testimony whereof I affix my signature.

ROBERT S. CADE.
